Primary Examiner — Robert M Spear*Assistant Examiner* — Marissa J Cash(74) *Attorney, Agent, or Firm* — Morland C. Fischer(57) **CLAIM**

The ornamental design for an airplane, as shown and described.

DESCRIPTION

FIG. 1 is a perspective view showing the top, left side and front of an airplane which forms our new design;

FIG. 2 is a top plan view thereof;

FIG. 3 is a left side elevational view thereof;

FIG. 4 is a bottom plan view thereof;

FIG. 5 is a right side elevational view thereof;

FIG. 6 is a front elevational view thereof; and,

FIG. 7 is a rear elevational view thereof.

The broken lines in the drawings represent unclaimed environmental subject matter and form no part of the claim.
